UNITED STATES PATENT OFFICE.

EDWARD FLEMING, OF COLUMBUS, OHIO, ASSIGNEE, BY DIRECT AND MESNE ASSIGNMENTS, OF ONE-HALF TO WILLIAM M. MYERS, OF LOCKBOURNE, OHIO, AND ONE-FOURTH TO WILLIAM D. HOPKINS, OF COLUMBUS, OHIO.

PICTURE-HOLDER.

1,023,072.

Specification of Letters Patent.

Patented Apr. 9, 1912.

Application filed April 17, 1911. Serial No. 621,623.

To all whom it may concern:

Be it known that I, EDWARD FLEMING, a citizen of the United States, residing at 182 Guilford avenue, Columbus, in the county 5 of Franklin and State of Ohio, have invented certain new and useful Improvements in Picture-Holders, of which the following is a specification.

My invention relates to picture hangers, 10 and is specially designed as an improvement on the construction embodied in my patent 894,197, dated July 22, 1908.

In addition to the meritorious features 15 illustrated in the patent above referred to, the present invention comprises adjusting means, consisting of elastic members, adapting the hanger for pictures of varying widths, and the device is also adjustable for use with pictures of varying depths.

The invention consists in certain novel 20 features of construction and combinations and arrangements of parts as hereinafter set forth and more clearly pointed out in the claim.

In the accompanying drawings I have 25 illustrated one example of the physical embodiment of my invention constructed according to the best mode I have so far devised for the practical application of the 30 principles.

While I shall hereinafter refer to the device as a picture hanger, it will of course 35 be understood that the device may be used in connection with all ordinary pictures, glass plates covering pictures, mirrors, and other articles of like nature.

In the drawings, in which like reference 40 characters designate similar parts: Figure 1 is a front elevation of the picture hanger, a fragment of a picture being illustrated in connection therewith, and Fig. 2 is a side or edge view of Fig. 1.

In its preferred form the hanger comprises a pair of complementary members, 45 usually made of twisted wire.

The suspending member is fashioned with a vertically disposed bar 1, formed at its upper end with a loop 2. At its lower end

two diverging legs 3, 3, extend from the bar 1, and the extremities of these legs are fashioned into clasping or gripping hooks 4, 4.

An adjustable, slid able member, 5, of similarly bent or twisted wire, is connected to the bar 1 of the suspending member by means of the loops or eyes 6, 7. These loops 55 are spaced a suitable distance apart in order to insure a well braced connection between the two members of the hanger. Diverging arms 8, complementary to the legs 3, are extended upwardly from the member 5, and 60 the extremities of these arms are provided with clasping or gripping hooks 9, 9, similar to the hooks 4. Upon reference to Fig. 2, it will be observed that the arms 8 are arranged in a plane inclined to the vertical 65 suspending member 1. This construction is desirable in order to provide means by which the picture may be best presented to view when suspended, for instance upon a wall, above the line of vision.

The nature of the metallic arms and legs 70 of the two members provides for an elastic adjustment of these parts to adapt them for varying widths of pictures. The slide- 75 able connection between the two members permits vertical adjustment of the parts to adapt them for varying depths of pictures. The friction between the loops 6 and 7 and the portion 1, is sufficient to hold them in 80 adjusted relationship. The friction re- 85 quired is only very slight, as it will be understood that the picture, which is gripped at its four corners by the hooks 4, 4, and 9, 9, is carried by the suspending member 1, which is attached to a hook, nail, or screw by means of the loop at its upper end.

While I have described a satisfactory 90 form of the invention, it will be understood that various changes may be incorporated therein, without departing from the spirit of the claim annexed hereto.

What I claim as new and desire to secure by Letters Patent is:—

The combination with a single bar formed 95 with a suspending loop at one end, and elastic, divergent legs each fashioned with an

end gripping hook, of an adjustable member comprising a short bar formed with an end loop and an intermediate loop surrounding and frictionally engaging said single 5 bar, and elastic arms diverging from the extensible member and provided with end gripping hooks.

In testimony whereof I affix my signature in presence of two witnesses.

EDWARD FLEMING.

Witnesses:

C. M. SHIGLEY,
IDA A. EVANS.
